Inventor
W.F. Fraser

UNITED STATES PATENT OFFICE.

WILLIAM FOBSTER FRASER, OF PORT ROBINSON, ONTARIO, CANADA.

WASHING MACHINE

Application filed October 7, 1922. Serial No. 593,056.

To all whom it may concern:

Be it known that I, WILLIAM FOBSTER FRASER, a subject of the King of Great Britain, and a resident of the village of Port Robinson, in the county of Welland, in the Province of Ontario, Canada, have invented certain new and useful Improvements in Washing Machines, of which the following is the specification.

10 My invention relates to improvements in washing machines and more particularly to plunger rings used with the vacuum type, and the object of the invention is to devise an improved plunger ring provided with a 15 vacuum chamber at its lower end which will quickly and efficiently do the work, while effecting a considerable economy in power.

A further object is to devise a plunger ring which will be so effective in operation 20 as to do away with the necessity of soaking the clothes overnight prior to introduction into the machine.

My invention consists of a plunger ring constructed and arranged all as hereinafter 25 more particularly described and illustrated in the accompanying drawing in which:

Fig. 1 represents a plan view of a plunger ring constructed according to my invention.

Fig. 2 is a side elevation thereof, and

30 Fig. 3 is a vertical section through the line 3—3, Figure 1.

Like characters of reference indicate corresponding parts in the different views.

My plunger ring is constructed of super- 35 imposed spaced apart upper, intermediate and lower rings 1, 2 and 3 respectively, adapted to be held in position relatively to one another by the vertically disposed straps 4.

40 5 is an inwardly inclined upper flange formed at the top of the upper ring portion 1, the angle of inclination of the flange being substantially forty-five degrees, and such flange being provided for the purpose 45 of preventing the water in the tub splashing over the top of the plunger ring.

The ring portions are provided with rolled over edges, and the lower ring portion 3 is provided with an inverted U-shaped annular 50 conduit 6 disposed inwardly of the wall of the ring portion which is concentric with the walls of the remaining ring portions 1 and 2. The inner wall of the conduit 6 is turned

inwardly at its lower end to constitute a horizontal flange 7.

8 is a bridge-piece extending across the top of the ring portion 1 and preferably secured to the flange 5 thereof, said bridge-piece having the vertical hole 9 adapted to receive the plunger operating rod 10 which 60 extends downwardly therethrough.

On the up stroke of the plunger a vacuum is created in the conduit 6 and on the downward stroke the water rushing in, fills the conduit 6, causing the expulsion of 65 the air therefrom out through the water and up through the clothes disposed in the centre of the plunger ring, the inwardly extending flange 7 forcing the water inwardly so that it will be driven up with more force on the 70 downward stroke of the plunger ring and thus create more effective agitation.

An outwardly extending horizontal flange 11 is provided at the lower end of the outer wall of the ring portion 3 which prevents 75 the lower edge of such wall cutting its way through the water without resistance, thus aiding in the effective agitation thereof.

From the above description it will be seen that I have devised a simple and effective 80 plunger ring of improved design which can be readily manufactured and which will be exceedingly efficient in use.

What I claim as my invention is.

1. In a washing machine, a plunger ring 85 having a peripheral conduit formed at the lower end thereof of substantially U-shaped cross section, the outer wall of the conduit coinciding with the ring proper, the lower edge of the outer wall of the conduit 90 turned outwardly to form a substantially horizontal flange, and the lower edge of the inner wall of the conduit turned inwardly to form a substantially horizontal flange, and the upper edge of the ring inclined inwardly.

2. In a washing machine, an agitator ring of the walled type comprising a plurality of spaced apart superimposed concentric annular wall sections, each open at top and bottom, means for holding the wall sections in their spaced apart position, and an inwardly extending annular conduit formed in the lower wall section constituting a vacuum chamber.

3. In a washing machine, an agitator ring

of the walled type comprising a plurality of spaced apart superimposed concentric annular wall sections, each open at top and bottom, means for holding the wall sections in their spaced apart position, and an inwardly extending annular conduit formed in the lower wall section constituting a vacuum chamber, the lower edge of the outer wall of

the conduit turned outwardly to form a substantially horizontal flange and the lower edge of the inner wall of the conduit turned inwardly to form a substantially horizontal flange and the upper edge of the upper wall section inclined inwardly.¹⁰

WILLIAM FOBSTER FRASER.
